Hand Control HB80, Announced Jul. 1, 2010 [Site visited Aug. 22, 2016] <http://www.linak.com/products/controls.aspx?product=HB80>.*

(Continued)

Primary Examiner — John Windmuller(74) *Attorney, Agent, or Firm* — Dykema Gossett PLLC(57) **CLAIM**

The ornamental design for a hand control, as shown and described.

DESCRIPTION

FIG. 1 is a top perspective view of a hand control according to my new and ornamental design,

FIG. 2 is a bottom perspective view thereof,

FIG. 3 is a top plan view thereof,

FIG. 4 is a bottom plan view thereof,

FIG. 5 is a left side view thereof,

FIG. 6 is a right side view thereof,

FIG. 7 is a front end view thereof; and,

FIG. 8 is a rear end view thereof.

The broken lines in the figures depict indicia that form no part of the claimed design.

1 Claim, 6 Drawing Sheets(56)
